DIVIDED LAST

Filed Nov. 2, 1927

UNITED STATES PATENT OFFICE.

GEORGE M. RAY, NEWTON CENTER, MASSACHUSETTS.

DIVIDED LAST.

Application filed November 2, 1927. Serial No. 230,482.

This invention relates to certain improvements in divided lasts of the type disclosed in my pending application Serial No. 148,057, in which the last is divided by a plane of separation which extends from the last bottom, in the shank portion, obliquely towards the top to heel end, a tongue and groove connection being provided between the sections, so arranged that they are connected by sliding the heel section on the forepart section towards the top of the latter.

In said prior construction, a spring actuated bolt, or pin, for locking the heel section to the forepart section was arranged in the heel section in approximately perpendicular relation to the top of the last and this arrangement was found to be unsatisfactory for several reasons. When a shoe is properly lasted the upper is drawn as tightly as practicable from the toe end of the last to the middle of its back end, so that it exerts a strong tension longitudinally of the last, and, on account of the fact that the plane of separation extends obliquely forward from the top towards the last bottom, the tension on the back end of the heel section tends to pull the same forwardly, and the locking bolt located as above described was not found to be effective in preventing all movement in this direction, and any movement which caused the last to shorten and the upper to be relaxed, even to a slight extent, at the time of the lasting operation, is vitally objectionable.

Another objection to my said previous construction was that it did not permit reassembling of the section in as convenient a manner as was desirable.

The objects of the present invention are to provide, in connection with a last having the important characteristics of my said prior construction an improved means for locking the sections together which will effectively prevent any relative shortening movement of the last sections due to longitudinal tension thereon, until the locking means is actually moved to permit separation of the sections, and which is also constructed and arranged to permit the sections to be readily restored to normal relation and the shoe to be readily relasted if desired.

I accomplish these objects in the manner hereinafter described and as illustrated in the accompanying drawings in which:

Fig. 1 is a side elevation of a last em-

bodying the invention and shown in position for lasting.

Fig. 2 is a longitudinal sectional view of the heel portion thereof. 60

Figs. 3 and 4 are, respectively, and views of the forepart and heel part sections when separated.

Fig. 5 is a sectional view, similar to Fig. 2, illustrating the unlocking and delasting 65 operation.

Fig. 6 is a similar view illustrating the operation of restoring the parts to normal position, and

Fig. 7 is a detail perspective view of a 70 portion of the rear end of the forepart section.

In general construction and arrangement the last herein described is practically identical to my previously described construction, comprising a forepart section *a* and a heel part section *b*, said sections being divided by a transverse plane of separation which extends obliquely rearward from the last bottom at a line preferably adjacent the 75 rear portion of the shank part to points closely adjacent the line of the top edge of the upper of a low cut shoe, when on the last, said plane of separation being met by another plane of separation which extends 80 from the rear end of the last in approximate parallelism with the top or heel surface, so that the top of the last is continuous or undivided and the forepart section has a 85 projecting heel portion *a*¹ integral therewith. A flat metal plate *c*, of the same thickness as the saw cut formed in dividing the last, is firmly secured, preferably by ordinary wood screws, to the surface on the forepart formed by the oblique cut which 90 extends from the last bottom, the plate *c* being formed in outline to cover the entire surface formed by the oblique cut, so that its edges are flush with the sides and bottom of the last and its inner end extends to meet 95 the surface which is formed by the horizontal plane of separation. In practice the plate is secured in position before the surface of the last is buffed, and is made of brass, so that its edge may be buffed down 100 when the last is finished and forms a smooth continuous surface with the last surface. The plate *c* is slotted from its bottom end, throughout the middle thereof to points at 105 a substantial distance from the inner or top end of the plate, the sides *c*¹ of said slot being undercut and extending convergently

from the bottom to a transverse square shoulder c^2 which forms the inner end of the slot, as shown in Fig. 7, a slot of tapering dove-tail construction being thereby formed.

5 A metal tongue plate d , of the same thickness as the plate c , is secured to the heel section b the side edges d^1 thereof being tapered and under cut to correspond to the sides c^1 of the slot, so that, when the heel part 10 section is placed on the forepart section and slid into position, the tongue plate will pass into the slot of the groove plate c and will become firmly wedged therein when the last sections are in their normal relative position, 15 in which position the end edge d^2 of the tongue will seat against the shoulder c^2 of the plate. In order that the top face b^1 of the heel section may also seat firmly on the projecting heel portion a^1 of the other section, a hard fiber plate e , of a thickness 20 corresponding to the width of the saw cut, is secured on one surface, or the other, formed by the saw cut which extends from the rear end of the last.

25 The heel section is bored to form a chamber b^2 , which extends from a point in the oblique face formed by severing the last located approximately midway between the inner end of the tongue plate d and its top 30 face b^1 and in a direction as nearly perpendicular to said oblique face as practicable. A coil spring f is disposed in said recess, and a bolt or hinge, having a flanged inner end and a rounded or semi-spherical outer end, 35 is arranged in said chamber b^2 , a thimble h being provided in the outer end of the chamber, in which the pin is slidably fitted, and which acts to limit the extent to which the pin may be forced outward. The plate c is provided with a hole c^3 , which, when the last sections are in their normal positions 40 relatively, is located in position to receive the outer end portion of the pin g , which is normally held by spring f , in a position in which its end portion protrudes to at least the thickness of plate c beyond the face of the heel section. The forepart section is bored from its top end to the plate c in alignment 45 with the chamber b^2 , so that the bore opens to the hole c^3 , and a metal bushing, or thimble j is fitted therein. The forepart section is also provided with the usual jack post thimble k which is located in front of, and as closely as practicable to the outer end of 50 the thimble j , which extends obliquely from the thimble k . The plate c is beveled at the middle portion of the shoulder c^2 , to form an inclined deflecting face c^4 , which extends outwardly from the inner end of the slot 55 towards the hole c^3 to points closely adjacent thereto. The last is provided with the usual metal bottom which will be formed in two sections m and n , the section n on the heel section being arranged to overlap plate d 60 thereon.

Assuming that the sections are disconnected, and are to be connected, the narrower end portion of the tongue plate d will be inserted in the wider portion of the slot in the groove plate c , the adjacent faces of the plate c and heel section b being held in contact while the sections are slid relatively into normal position. The action of placing the sections together, as in Fig. 6, causes the pin g to be pressed inward by 75 its engagement with the forepart section and when the rounded outer end of the pin is engaged with the inclined face c^4 it will be forced inward until its outer end is flush with the face of the heel section and bears 80 on the surface of the plate c , so that when the sections have been moved into normal relation, the pin g will be forced into the hole c^3 , locking the parts firmly in this position, the arrangement being such that, at 85 the same time, the sides of the slot and tongue will become firmly wedged together and the end d^2 of the tongue will become firmly engaged with the shoulder c^2 . In 90 this position the pin g , which will be closely fitted in the thimble h , will also be closely fitted in the hole c^3 , and will extend through the plate c approximately at right angles thereto, so that, when the shoe is lasted and drawn tightly from the toe to the middle of 95 the back end of the last, the tendency thereby caused to slide the heel section forwardly on the forepart section, so as to shorten the last, will be positively and effectively resisted, and at the same time the sections will 100 be as firmly connected, for all practical purposes, as if they had not been separated.

When the shoe is lasted the last will be supported on the ordinary jack post, which will be located in thimble k , as in Fig. 1, 105 but, for removing the shoe from the last, a special jack is provided, having a post p adapted to fit in thimble j , and having its end portion p^1 reduced to the diameter of the hole c^3 , the portion p^1 being of a length 110 equal to the thickness of the plate c . When the shoe is to be removed from the last, the last will be placed on the post p and pressed down, so that its reduced end portion will engage the end of pin g , which will be forced 115 upward thereby until the shoulder on the post engages the plate c , in which position the pin g will have been entirely freed from the hole c^3 , as shown in Fig. 5. When 120 this occurs, the heel section will be slipped forward by the tension of the shoe thereon and then the operator, by pulling on the back end of the shoe, will be able to remove it easily without in any way stretching or straining the shoe upper. If the shoe is to 125 be relasted the heel section will be placed in position in the heel part of the shoe and then the shoe will be drawn onto the forepart, as the heel part is pressed down into position thereon, as previously described, without 130

over straining the upper, or requiring the use of a shoe horn.

The above described construction also possesses all the advantages of my previously disclosed construction and may be manufactured at a low cost.

I claim:

1. A last having heel and forepart sections divided by a transverse plane of separation 10 extending obliquely from the bottom towards the top and rear end thereof and forming oppositely disposed contacting faces thereon, connecting means disposed on said faces and arranged to interlock as the heel section is 15 moved from the bottom towards the top of the forepart section with said faces in contact, a bolt slidably mounted in said heel section in approximately perpendicular relation to the face thereof, and means for yieldably 20 holding said bolt with its end portion protruding beyond said face, said forepart section having a deflecting face arranged to retract said bolt as said heel section is moved towards the top thereof in interlocked relation and a recess to receive said end portion 25 as said sections are moved into normal relation to lock the same against opposite movement, said recess opening to the top of the section to permit manual retraction of the 30 bolt.
2. A last having heel and forepart sections divided by a transverse plane of separation 35 extending obliquely from the bottom towards the top and rear end thereof and forming oppositely disposed contacting faces, tongue and groove connecting means disposed on said faces and arranged to interlock as said heel section is moved slidably with said faces in contact towards the 40 top of the forepart section, abutting means on said sections arranged to limit said movement when the sections are in normal relation, a locking bolt reciprocally mounted in said heel section in approximately perpendicular 45 relation to its said face, and having spring

actuated means for normally holding said bolt with its end portion extending beyond said face, and means on said forepart section for retracting said bolt as said sections are moved in interlocked relation towards their 50 abutting position, said forepart section having a recess arranged to receive the bolt end portion as the sections are moved into abutting relation, to lock the same against retraction, and having a post aperture leading 55 from its top to said recess, to cause retraction of the bolt when the last is supported on a post inserted therein.

3. A last having heel and forepart sections divided by a transverse plane of separation 60 extending obliquely from the bottom towards the top and rear end thereof and forming oppositely disposed contacting faces, a flat metal plate mounted on the face of said forepart section having an undercut slot leading from its bottom end and an opening therethrough beyond the upper end of said slot, a metal tongue mounted on said heel section and arranged to be locked in said slot as the heel section is slidably 65 moved on the forepart section towards the top of the latter, and a bolt reciprocally mounted in said heel section in approximately perpendicular relation to its said face and having spring actuated means to move 70 the end portion thereof into said opening when the sections are moved into normal relation, the plate on said forepart section having a deflecting face extending from the inner end of its slot towards its said opening 75 arranged to cause retraction of said bolt as said heel section is moved towards its normal position on the forepart section, and said forepart section having a passage 80 leading to said opening arranged for manual retraction of said bolt from the top of the last.

In testimony whereof, I have signed my name to this specification.

GEORGE M. RAY.
